UNITED STATES PATENT OFFICE.

ALBERT B. DISS, OF NEWARK, NEW JERSEY, ASSIGNOR TO THE BASSICK CO., OF BRIDGEPORT, CONNECTICUT, A CORPORATION OF CONNECTICUT.

CASTER.

1,304,748.

Specification of Letters Patent. Patented May 27, 1919.

Application filed August 17, 1918. Serial No. 250,365.

To all whom it may concern:

Be it known that I, ALBERT B. DISS, a citizen of the United States, residing at the city of Newark, county of Essex, State of New Jersey, have invented certain new and useful Improvements in Casters; and I do declare the following to be a full, clear, and exact description of the invention, such as will enable others skilled in the art to which it applies to make and use the same.

This invention relates to certain new and useful improvements in furniture leg mounts and pertains more particularly to leg mounts employed in connection with casters.

15 The primary object of the invention is to provide an improved means for retaining the caster against separating movement with relation to the mount, and briefly proposes to employ a clip which is attached to the back 20 of the foot of the leg and which has spring arms extending outwardly therefrom to engage on opposite sides of the caster pintle and with a head or knob formed on the latter so as to limit longitudinal movement of the 25 pintle with respect to the furniture foot.

Further and other objects will be later herein set forth and of themselves manifested in the course of the following description.

30 In the drawings:—

Figure 1, is a rear fragmentary elevation showing the invention applied to a furniture leg;

Fig. 2, is a section on line 2—2 of Fig. 1;

35 Fig. 3, is a section on line 3—3 of Fig. 1; and

Fig. 4, is a detail perspective view of the clip.

In proceeding in accordance with the present invention, the leg 1, of angle type, has the angular portions 2, 2. The foot has a bottom 3, perforated at 4 to receive the pintle P of the caster C, the foot being integral with the back 5, which latter has the top 6 also integral therewith, the top being perforated at 7 to receive the upper end portion of the pintle P. The back is formed with integral clamping members 8 connected thereto by curved portions 9, to leave spaces 45 10, for the purpose of accommodating the portions 2, so that should the latter not be uniform as to width or thickness, such dimensional variance will be provided for. A spring plate 11 is riveted at 12 to the back 55 plate by the eyelets shown and has its lower

end deflected so as to bear against the angular portions 2, on the inner faces thereof, so as to hold the portions 2 under constant pressure or tension in engagement with the clamps 8.

The present invention pertains particularly to means for retaining the pintle in its assembled relation to the foot, such means embodying a clip provided with an attaching plate 11 which may be brazed as indicated at 12 to the back plate or otherwise suitably secured to or carried by the latter. This plate projects above the top 6, and is formed with a pair of opposed and spaced spring arms 13 which preferably converge 70 at their free ends as depicted in Fig. 4, so as to lie closely adjacent to the pintle, the latter being received in the space between the arms as shown in Fig. 3. The pintle has an enlarged head or knob 14 beneath which 75 the arms 13 are disposed so as to limit downward movement of the pintle by virtue of the head 14 thereof engaging the upper sides of the arms 13.

The mode of securing of the plate 11 to 80 the back of the foot is immaterial, except that the securing must be of such character as to rigidly support the plate. It will be thus apparent that since the spring arms are separable by spreading thereof that the 85 pintle can be secured in position and removed by simply forcing same against the spring arms, which latter will spread and then return to normal position, the spreading being accomplished by making the head 90 or knob 14 of somewhat rounded form so as to serve as a wedge in forcing the spring arms apart. The tension of the spring arms is such however, that quite a little force is required to separate same, consequently no 95 danger of accidental separation exists.

What is claimed is:

1. In a furniture caster leg mount, a foot having a back, a top and a bottom, the top and the bottom being perforated to receive the caster pintle, a clip having a plate secured to the back of the foot and having a pair of spaced spring arms extending over the top and a knob on the pintle engageable with the arms to limit downward movement of the pintle, said arms being capable of being spread to permit the passage of the knob upon the expenditure of force exerted on the pintle.
2. In a furniture caster leg mount, a foot 110

having spaced upper and lower perforated portions to receive the pintle, a caster having a pintle which is provided with an engageable part, and a clip carried by said foot 5 and extending above and parallel to said upper portion and adapted to engage said engageable part of the pintle when the latter is inserted through said perforated portions.

3. In a furniture caster mount for angular 10 legs, a foot embracing the outer and inner faces of said leg and having spaced and perforated upper and lower plates extending

within the leg, a caster having a pintle which is inserted through said plates, and inter-engaging means carried respectively by said pintle and by said foot and overhanging said upper plate whereby the pintle may be locked as against accidental displacement. 15

In testimony whereof I affix my signature in presence of two witnesses.

ALBERT B. DISS.

Witnesses:

J. WILLIAM RUPPRECHT,
DANIEL B. DISS.
